Inventor
Walter S. Reynolds,

UNITED STATES PATENT OFFICE.

WALTER S. REYNOLDS, OF CLAYTON, DELAWARE.

WINDOW-SHADE SUPPORTER.

SPECIFICATION forming part of Letters Patent No. 406,474, dated July 9, 1889.

Application filed February 12, 1889. Serial No. 299,561. (No model.)

To all whom it may concern:

Be it known that I, WALTER S. REYNOLDS, a citizen of the United States, residing at Clayton, in the county of Kent and State of Delaware, have invented new and useful Improvements in Window-Shade Supporters, of which the following is a specification.

My invention relates to improvements in window-shade supporters; and it consists in certain novel features hereinafter described and claimed.

In the accompanying drawings, Figure 1 is a front elevation showing a window provided with my improvements and showing a window-shade or curtain supported thereby. Fig. 2 is a perspective view of the rack-bar, and Fig. 3 is a perspective view of the supporting-rod and the rear end of the curtain-bar.

In carrying out my invention I employ two rack-bars A, which may be constructed of any suitable material, either of sheet metal or cast, as may be preferred; and I secure these rack-bars to the sides of the window-frame B, as clearly shown in Fig. 1. The rack-bars are secured to the window-frame in such a position that their front edges project forward beyond the window-frame, and the said front edges are bent inward, forming the flanges C. These flanges are provided at various points of their length with the notches D, as shown.

The ends of the curtain-bar E are engaged under the flanges C of the rack-bars and move vertically in the spaces between the said flanges and the front side of the window-frame. The ends of the said curtain-bar are provided with the notches F and with the vertical openings G, leading downward from said notches, and in which the supporting-rod H are journaled. The said supporting-rod consists of long cylindrical rods which extend downward from the curtain-bars through guides or keepers I, secured to the window-frame, and are provided at their upper ends with the crank-arms J, which move through the notches F, and are adapted to engage the notches D in the rack-bars and thereby support the curtain-bar. In its rear side the curtain-bar is provided with the vertical grooves K, which lead upward from the notches F and are in vertical alignment with the openings G. When inserting the supporting-rod

into position in the ends of the curtain-bar, the said rods are passed downward through the groove K and the opening G until the 55 crank-arm J reaches the notch F, when the said supporting-rod is turned forward, so as to bring the crank-arms through the said notch, as will be readily understood. The curtain-bar is supported at any desired height 60 by turning the supporting-rods so that their crank-arms will engage the notches of the rack-bars, as shown in Fig. 1, and as will be readily understood.

From the foregoing description, taken in 65 connection with the accompanying drawings, it will be seen that I have provided an extremely simple, cheap, and efficient device by which the window shade or curtain can be supported at any desired height, so as to admit light through the entire window or admit light through the upper portion of the window and shield the lower portion of the same, as may be desired. The supporting-rods can be readily operated from their lower ends, and 70 the greater portion of their length will be covered by the flanges of the rack-bars, so that they will be prevented from injuring any ornaments or drapery that may be hung over the window. The device can be quickly adjusted 75 to the desired height, as it is only necessary to turn the supporting-rods so that their crank-arms will be thrown out of engagement with the rack-bars, when the device can be readily moved either up or down, as will be 80 understood. The ends of the curtain-bar are guided in the vertical movement of the device, and are also prevented from falling forward from the window-frame by the flanges 85 of the rack-bars.

My device can be applied to any window, and its advantages are thought to be obvious.

Having thus described my invention, what I claim, and desire to secure by Letters Patent, is—

1. In a window-shade supporter, the combination of the rack-bars secured to and projecting forward from the window-frame and provided at their front edges with inwardly-projecting notched flanges, the curtain-bar 100 having its ends moving between the window-frame and the notched flanges and provided with longitudinal notches, and the supporting-rods journaled in the ends of the curtain-

95

bar and provided with horizontal crank-arms playing in the notches in the ends of the curtain-bar and engaging the notches in the flanges of the rack-bars, as specified.

5 2. The combination of the rack-bars, the curtain-bar provided in its ends with the notches F, the openings G, leading downward from said notches, and the grooves K, leading upward from said notches, and the supporting-rods adapted to be inserted through the grooves K and journaled in the openings

G, and provided with crank-arms playing in the notches F and engaging the rack-bars, as specified.

In testimony that I claim the foregoing as my own I have hereto affixed my signature in the presence of two witnesses.

WALTER S. REYNOLDS.
